R. H. PARKER

PILE WIRE

Filed Jan. 6, 1922

FIG. 1.

FIG. 2.

FIG. 3.

INVENTOR:

R. H. Parker,

BY

E. D. Bradenick
ATTORNEY.

UNITED STATES PATENT OFFICE.

RILEY HERBERT PARKER, OF WINTHROP, MASSACHUSETTS, ASSIGNOR TO GILLETTE SAFETY RAZOR COMPANY, OF BOSTON, MASSACHUSETTS, A CORPORATION OF DELAWARE.

PILE WIRE.

Application filed January 6, 1922. Serial No. 527,336.

To all whom it may concern:

Be it known that I, RILEY HERBERT PARKER, a citizen of the United States, residing at Winthrop, in the county of Suffolk 5 and State of Massachusetts, have invented certain new and useful Improvements in Pile Wires, of which the following is a specification.

My invention relates to pile wires such as 10 are used in looms for weaving cut-pile fabrics and have detachable, transversely-flexible cutting blades which are retained in the wires during use by utilizing the elasticity of the blades to hold them in engagement 15 with suitable positioning devices whereby the blades are maintained in operative relation to the wires. More particularly, the present invention is an improvement on the subject matter of an application (Serial No. 20 420,963) for U. S. Letters Patent filed November 1, 1920, by Ralph E. Thompson, which shows and describes a pile wire and blade of the character above referred to, the wire being provided with stops which over- 25 hang the ends of the blade when in operative position and with a lateral opening into which one end of the blade is fixed during insertion and removal. The objects of my 30 improvements are, primarily, to increase the facility with which the blade can be inserted and removed and to simplify the formation of the blade-receiving recess of the wire.

In the accompanying drawing, Figure 1 35 is a side elevation of a portion of a pile wire made in accordance with my invention.

Figure 2 is a plan view of the same with the blade removed, and

Figure 3 is a side view of a detachable 40 blade shown in Figure 1.

In the drawing, 2 indicates the front or free end portion of a pile wire which is of uniform height throughout that part of its length at which the blade is located, and 3 45 indicates a blade which is substantially triangular in shape and has upwardly-converging front and rear edges, of which the rear edge 4 is the cutting edge. The lower edge of the blade 3 when in operative position in the 50 wire is seated on the bottom of a blade-receiving recess which may be formed by milling a groove 5 in the upper edge of the wire, the bottom of the groove being indicated by the dotted line 6, Figure 1, and the blade 55 stop at the rear end of said recess may con-

sist of a pin 7 passing transversely through the wire in position to overhang the rear end of the blade. At the opposite end of the blade-receiving recess there is a transverse opening 8 provided with an under-cut front wall 9 which overhangs the front end of the blade when in operative position and prevents it from moving upward or forward, and in the particular construction illustrated this wall 9 is formed by pressing together 60 those portions of the wire which are separated by the front end of the milled groove 5 in front of the opening 8, thereby not only closing the groove at this point but also providing bevelled surfaces 10 on the sides of 65 the wire.

The blade 3 is transversely flexible and is inserted by introducing its rear end into the blade-receiving recess near the rear end of the latter, with its front end bent to one side 70 of the wire adjacent to the opening 8, and then pushing it downward and rearward until its front end is in position to spring into place behind the end wall 9, whereupon the blade is released and resumes its normally flat condition, being held in position so long as it remains flat by the overhanging wall 9 and the pin 7 at its corresponding ends. To remove the blade it is necessary to bend its front end laterally beyond one side 75 of the end wall 9 and then draw it forward and upward out of the recess, the operations of insertion and withdrawal being facilitated by the bevelled surfaces 10 which reduce the extent to which it is necessary to 80 flex the blade.

The construction above described has the advantages that the blade-receiving recess can be easily and accurately formed in a solid wire and that the greater part of the 85 blade projects above the upper edge of the wire when seated therein, so that the blade can be readily engaged for flexing it during insertion and removal. For this reason it is not essential to provide a lateral opening at 8 on both sides of the wire, although this is preferably done because it simplifies the operations involved in constructing the 90 wire.

I claim:

1. A pile wire provided with a blade-receiving recess in its upper edge and with a lateral opening at one end of the recess, in combination with a flexible cutting blade having a substantially triangular shape with 105 11

upwardly-converging front and rear edges and located mainly above the top of the wire when seated on the bottom of the recess, and retaining means overhanging the ends of the 5 blade near its lower edge but leaving the blade free to be flexed at one end into said opening.

2. A pile wire provided with a blade-receiving recess in its upper edge and with 10 a lateral opening communicating with the front end of said recess and having an undercut front wall, the wire being laterally bevelled in front of said opening, in combination with a flexible cutting blade having a substantially triangular shape with 15 upwardly-converging front and rear edges and located mainly above the top of the wire when seated on the bottom of the recess, and retaining means overhanging the rear 20 end of the blade near its lower edge.

3. A pile wire provided with a blade-receiving groove in its upper edge and with a lateral opening communicating with said groove and having an undercut front wall, 25 said wire being of substantially uniform height throughout the length of the groove, in combination with a flexible cutting blade adapted to be seated on the bottom of the groove and having a substantially triangular shape with upwardly-converging front and rear edges, and a blade stop crossing the groove at the rear end of the blade in position to overhang the latter, the groove being closed at said undercut wall by lateral deflection of the material in which the 30 groove is cut.

Signed at Boston, Mass., this 4th day of January, 1922.

RILEY HERBERT PARKER.
